COMBINATION SPARE TIRE AND WHEEL CARRIER ASSEMBLY

Frank Cooper, 820 W. Lawrence,
Charlotte, Mich. 48813

Filed Nov. 21, 1966, Ser. No. 4,756

Term of patent 7 years

(Cl. D54—1)

The broken lines in FIGURE 3 are only shown for illustrative purposes.

I claim:

The ornamental design for a combination spare tire and wheel carrier assembly, substantially as shown and described.
